UNITED STATES PATENT OFFICE.

ELLIS E. ERICKSON, OF IRVINGTON, NEW JERSEY, ASSIGNOR TO NEWARK SIGN COMPANY, OF NEWARK, NEW JERSEY, A CORPORATION OF NEW JERSEY.

DESIGN FOR AN OUTDOOR SIGN.

52,008.

Specification for Design. Patented May 7, 1918.

Application filed April 3, 1917. Serial No. 159,554. Term of patent 7 years.

To all whom it may concern:

Be it known that I, ELLIS E. ERICKSON, a citizen of the United States, residing in Irvington, county of Essex, and State of New Jersey, have invented a new, original, and ornamental Design for Outdoor Signs, of which the following is a specification, reference being had to the accompanying drawings, which form a part thereof.

The figure is a front view of an outdoor sign illustrating my new design. At opposite ends of the signboard proper are end posts, on the front of each of which, between its top and bottom, is a diamond shaped ornamentation and above and below the dia-

mond are longitudinally extending figures the ends of which, adjacent to the diamond, are shaped to approximately conform with the adjacent ends of the diamond.

I claim—

The ornamental design for an outdoor sign, as shown and described.

In testimony of which invention I have hereunto set my hand, at Newark, N. J., on this 20th day of March, A. D. 1917.

ELLIS E. ERICKSON.
